UNITED STATES PATENT OFFICE.

DAVID L. BARNES, OF CHICAGO, ILLINOIS, ASSIGNOR TO ALEXANDER J. LEITH,
OF NEW YORK, N. Y., AND WILLIAM R. STIRLING, OF CHICAGO, ILLINOIS.

RAILWAY-CAR.

SPECIFICATION forming part of Letters Patent No. 409,002, dated August 13, 1889.

Application filed April 9, 1889. Serial No. 306,557. (No model.)

To all whom it may concern:

Be it known that I, DAVID L. BARNES, of Chicago, Cook county, State of Illinois, have invented a new and useful Improvement in 5 Car-Construction, of which the following is a full, true, and exact description, reference being had to the accompanying drawings.

My invention relates to details of construction of railway-cars, and is shown as embodied in a freight-car in which wood forms a 10 part of the structure. I can, however, if desired, make my car entirely of metal.

My invention will be readily understood from the accompanying drawings, in which—

15 Figure 1 represents an exterior end elevation of the end of the side of the car; Fig. 2, an inside elevation of Fig. 1; Fig. 3, an inside elevation of the end of the car, showing the sides partly in section; Fig. 4, a plan view 20 of the floor of the car, showing the sides and end in section; Fig. 5, a plan of the roof of the car; Fig. 6, a view of the bottom of the car; Fig. 7, a detail of the floor of the car and adjacent parts, showing the structure and arrangement of the truss-rods; Fig. 8, a view of 25 the end of the car at right angles to Fig. 7; Fig. 9, a detail of the truss-rod struts and bracing of the same; Fig. 10, a view partly in section showing the detail of construction 30 of the corner of the car; Fig. 11, a section through part of the side of the car, showing the posts and the method of attaching the wood-work to the same; Fig. 12, a modification 35 of the method of attaching the wood-work to the post; Fig. 13, a vertical section of the lower part of the post-attaching mechanism; Fig. 14, an exterior elevation of the 40 lower part of the post, showing the metallic construction at that point; Fig. 15, a transverse section through the middle of the car, showing the water-shed plate arranged over the sliding door of the car; and Fig. 16, a section 45 showing the detail of the construction of the corner-posts of the car.

The outside of my car is generally constructed of corrugated metal A and the roof of similar corrugated metal B. The corrugated-metal sheets B, forming the roof, are united to the sides by cornice-pieces C, having 50 corrugations fitting the corrugations of the side of the roof, and preferably having

projecting lips, as at D, for throwing the drip-water away from the sides of the car. These cornice-pieces run underneath the sheets B and outside of the sides A, as clearly shown 55 in Fig. 15.

In the center of the car a third corrugated piece E may be inserted, which serves as a water-shed to protect a door, which may be arranged beneath it. This is inserted between the parts B and C, as shown. Upon the top of the roof the ordinary running-board F may be arranged, as shown. The sides are supported upon posts G, which serve likewise as the support for the planking 65 within. This planking may be attached in various ways.

In Fig. 11 joists H are arranged over the flanges of the posts G, and the planking J is bolted to the same, as shown in Fig. 12. The 70 posts themselves are filled with suitably-shaped wooden uprights nailed thereto, and the planking J is directly nailed to such wooden filling. The posts are extended upward, fitting the corrugation of the side beneath the cornice-pieces, as shown, and within these posts are riveted the carlings K, extending across the car and fitting the corrugations of the roof. The lower ends of the posts G 75 rest against the support L, Fig. 13, attached 80 to the side sill N of the car, and, as shown, integral therewith. Covering the lower ends of these posts are the suitably-shaped continuous clamps N³, preferably longitudinally corrugated and shaped at the posts to cover 85 the same and hold them firmly against the side sills N, where these clamps are bolted to the side sills by bolts O, as shown. These clamps overlap each other on the corners, as plainly shown in Fig. 10. The longitudinal 90 beam J' may be bolted inside of these side sills, thereby serving to stiffen the same, and may be recessed for the reception of the bolts O. Similar beams may be used inside at the ends.

The construction of the corner-posts is shown in Figs. 7, 10, and 16, where G represents one of the side posts, and G' one of the end posts, which in their relation to each other are clearly shown in Fig. 16. The side 100 and end sheets A A' come in contact with the posts G G', and the corner-cap P, suitably

shaped, protects the otherwise exposed ends of the side and end sheets. The side and end sills may be fastened together by a triangular brace A', Fig. 10, where the relations of these sills are clearly shown. The side sill extends far enough to support the lower part of the post G. The end cornices C' are shaped at the ends to cover the corner-caps and the side cornices, as indicated in Fig. 1.

10. The car-body proper is supported upon six longitudinal sills, of which the side sills are shown at N, the intermediate sills at N', and the center sills at N². These sills are supported from longitudinal truss-rods, which truss-rods themselves are supported upon the trussed body-bolsters R, as shown in Fig. 8. The truss-rods S pass through the end sills T and have nuts or suitable fastenings on the ends thereof to hold them in position. They 20 then pass over the trussed bolsters, as shown, and then beneath the struts V, as clearly shown. These struts V are bolted or suitably fastened to the sills N N', as shown in Fig. 9, the center sills N² resting directly on the bolsters, as shown in Fig. 3. This trussed bolster has its lower part made of corrugated metal, as clearly shown in Figs. 6, 7, and 8, the corrugations extending from beyond the flat center part toward the sides. The center 30 is preferably provided with an opening for the king-bolt and the center plate, as indicated. The vertical end flanges of the parts R are bolted or suitably attached to the top member W of the truss, which serves likewise as a support for the floor-planks of the car. The struts themselves may be braced by a transverse brace X, which starts from the center sill, Fig. 9, and is attached to the outside strut V and to the intermediate strut between its points of end attachment. The part 40 of the trussed bolster over the center plate is preferably strengthened by two angle-irons Y, suitably fastened thereto. The floor itself is bolted upon the beams Z, which are fastened to the longitudinal sills, and which serve likewise as stiffeners for these longitudinal sills. The construction of the longitudinal sills may be readily somewhat varied, so as to employ angle-iron instead of channel-bars, as shown.

I have not shown the detail of the method of fastening of all the parts together, which may be by riveting or bolting, or in any suitable manner.

55. What I claim as my invention, and desire to secure by Letters Patent, is—

1. A metallic car, a metallic cornice intermediate between the sides and the roof and attached to both, and corrugated to fit the corrugations of the side and the roof, substantially as described.
2. The metallic cornice C, herein described, corrugated to fit the corrugations of the side, and provided with an external lip D, substantially as and for the purposes described.
3. The combination of the side posts G with

a longitudinal side sill projecting outward and serving as a base for said side posts, substantially as described.

4. The truss-rod struts V, made of pressed steel, attached to the sills and braced by piece X, extending in a downwardly direction upon the side of the car inward and attached to the side sill, the intermediate sill, and the center sill, thereby preventing the failure of the sills under a heavy load and acting as a lateral brace as well as a strut on the side sills, substantially as described.

5. The lateral brace X, of pressed steel, in combination with three longitudinal sills, to each of which it is attached, and the truss-rod struts V, for supporting the sills, substantially as described.

6. The combination of the center plate with the stiffening angle-irons Y, substantially as described.

7. The pressed-steel body-bolster R, longitudinally corrugated intermediate the side and center sills, substantially as described.

8. The combination of the corrugated pressed-steel body-bolster R with the top member W, forming a complete truss, substantially as described.

9. The combination, with the sills N' N², of longitudinal wooden stringers G, serving as stiffeners therefor and for the attachment of the flooring, substantially as described.

10. The combination of the corrugated sides A A' and the corner-cap P, fitting the said corrugations and covering the ends of said pieces A A', substantially as described.

11. The combination of the interlocking corner-posts G G' with the corrugated sides and ends fitting the same, substantially as described.

12. The combination of the vertical posts G G' with a clamp N³, surrounding the same and holding the posts upon the lower support, substantially as described.

13. The combination of the post G, provided with flanges, the strips H, locking said flanges, and the corrugated side A, fitting the post, substantially as described.

14. The hollow post G, provided with a wood filler attached thereto, in combination with the beam J, nailed to the lining of the post G, substantially as described.

15. The combination of the roof B, cornice C, and intermediate water-shed E, substantially as described.

16. The combination of a side post G, a carling K, fitting the same, and likewise fitting the corrugations of the corrugated roof, substantially as described.

In testimony whereof I have signed my name to this specification in the presence of two subscribing witnesses.

DAVID L. BARNES.
